UNITED STATES PATENT OFFICE.

ULRICH ANDERSON, OF MILWAUKEE, WISCONSIN, ASSIGNOR TO S. & G. MFG. CO., OF MILWAUKEE, WISCONSIN, A CORPORATION OF WISCONSIN.

SHIFTING-SIGN MACHINE.

Application filed October 19, 1921. Serial No. 508,889.

To all whom it may concern:

Be it known that I, ULRICH ANDERSON, a citizen of the United States, residing at Milwaukee, in the county of Milwaukee and State of Wisconsin, have invented certain new and useful Improvements in Shifting-Sign Machines, of which the following is a specification, reference being had to the accompanying drawing, forming a part 10 thereof.

This invention relates to machines or apparatus for automatically shifting a series of signs or display holders at intervals one after another into and out of view.

The main objects of the invention are to adapt such machines to be operated by either direct or alternating electric current according to the nature of the available source of supply in different places; to equalize the load on the machine throughout the circuit of the signs or display holders so that universal motors which are designed for operation by either direct or alternating current, and the speed of which fluctuates widely 20 under varying loads, may be used; to provide for variation of the speed of the shifting mechanism and the length of exposure of the signs; to provide for illumination of the exposed signs when natural light is insufficient therefor; to facilitate removing and replacing the signs or display holders and changing the advertising or other matter thereon; and generally to improve the construction and operation of machines 30 of this class.

It consists in the construction, arrangement and combination of parts as herein-after particularly described and pointed out in the claims.

In the accompanying drawing like characters designate the same parts in the several figures.

Figure 1 is a view partly in front elevation and partly in vertical longitudinal section on the line 1—1, of Fig. 3, of a shifting-sign machine embodying the invention; Fig. 2 is a vertical cross section of the machine on the line 2—2, Fig. 1; Fig. 3 is a similar section on the line 3—3, Fig. 1; and Fig. 4 is a partial horizontal section of the machine on the line 4—4, Fig. 2.

The casing, which encloses the signs or display holders and the mechanism for shifting them one after another into and out of view, comprises end plates 1, which may be

made of cast metal, flat bars 2, and angle bars 3 and 4 connecting the end plates, and sheet metal top, back and front sections 5, 6 and 7, closing the casing at the top and back and at the front of the forwardly extending base or lower part of the casing below the sight openings between the cross bars 2 and 3.

The end plates 1 are formed or provided at and adjacent their front edges with vertical flanges 9, between which are inserted and held panes or plates 10 and 11, of glass or transparent material, closing the sight openings through which the stationary and shifting signs are displayed.

Flanged guide plates 13 are fastened to the end plates inside of the casing, forming with the inner flanges 9, brake shoes or bars 14 and 15, and plates 16, guideways for the shifting signs 17. These guideways, which are located opposite the sight openings in the casing, and are parallel with each other, form continuous circuits for trunnions 18, with which the ends of the signs 17 are provided. Each guideway comprises two parallel vertical stretches or parts, connected at their upper and lower ends by substantially parallel transverse stretches or parts.

Link belts or chain 20, mounted on sprocket wheels 21, 22, 23, 24, and guided by the flanges on the guide plates 13 along the vertical parts and the upper transverse parts of the guideways, are provided on their inner sides with lugs 26, which are directly opposite each other and adapted by engagement with the trunnions 18 of the signs 17, to pick up the signs one at a time from the front ends of the lower transverse parts of the guideways, and transfer or shift them from the lower sight opening upwardly, 95 backwardly and downwardly into engagement with the rear ends of said lower transverse parts of the guideways, which are curved upwardly, as shown in Figs. 2 and 3, so as to deflect the signs forwardly out of 100 the path of the lugs 26.

The sprocket wheels 21, which support and guide the chains 20 at the upper ends of their runs, are journaled on pins fastened to and projecting inwardly from the end plates 1, and project at their peripheries through the flanges of said guides. The sprocket wheels 22, around which the chains 20 are guided at the lower ends of their runs, are fixed on a shaft 28 extending longitudi- 110

nally through the casing and having bearings 29 on the end plates 1. The sprocket wheels 23 are journaled on studs projecting inwardly from the end plates of the casing 5 below the guide plates 13, in position to direct the chains 20 in alignment with the front vertical stretches or parts of the guideways. The sprocket wheels 24 are journaled on arms 31, which are pivoted to the end plates 1 of the casing and pressed by springs 32 toward the front runs of the chains 20, so as to hold the sprocket wheels in yielding engagement with the chains and take up slack in the chains.

15 The brake shoes or bars 14 are adjustably connected by screws 34 with ledges 35, projecting inwardly from the end plates 1 of the casing, and are held by springs 36 in yielding engagement with the trunnions 18 20 of the signs as they pass rearwardly through the upper transverse parts of the guideways.

The brake shoes or bars 15 are adjustably connected by screws 38 with the inturned marginal flanges on the rear edges of the end plates 1, and are yieldingly held by springs 39 in engagement with the trunnions 18 of the signs as they pass downwardly through the rear vertical stretches of the guideways.

30 Leaf springs 41, fastened at their upper ends to inwardly projecting brackets 42 on the end plates 1, are arranged as shown in Fig. 2, to engage with the upper edges of the signs 17 as they pass from the upper 35 transverse into the rear vertical stretches of the guideways, and tilt them slightly forward, so that their lower edges as they descend will clear and pass behind the rear sign in the lower transverse stretches of the 40 guideways, which serve as a magazine to hold a considerable or any desired number of signs assembled together facing the lower sight opening in the front of the casing. The lower ends of the springs 41 are curved 45 forwardly so as to shift the signs as their trunnions are brought into engagement with the rear ends of the lower transverse parts of the guideways, and press and hold them together facing the sight opening in the casing, with the front sign in position to be 50 picked up by the lugs 26 on the chains. The lower transverse parts of the guideways which constitute the magazine for the signs, are preferably inclined slightly downward 55 towards the sight opening, as shown in Figs. 2 and 3, to assist in shifting the signs towards the sight opening into position to be picked up by the chains.

An electric motor 44, preferably of the 60 so-called universal type, is mounted in the lower part of the casing midway between its ends, on a saddle 45, which is supported at its ends on the angle bars 4. A pulley 47, on the motor shaft, is connected by a belt 65 with a cone or stepped pulley 49 on a shaft

50, mounted parallel with the motor shaft and transversely to the shaft 28 in a gear case or housing 51, which is supported on the angle bars 4, as shown in Figs. 1 and 2. The shaft 50 is provided with a worm 53, 70 which meshes with a worm gear 54, fixed on the shaft 28 in the gear case 51.

The motor shaft and the shaft 50 project at their rear ends through the back of the casing, and the pulleys 47 and 49 are located 75 outside of the casing, to facilitate shifting the belt for varying the speed of the motor and thus changing the rate of travel of the chains to lengthen or shorten the interval of exposure of the signs to view.

In order to regulate the speed of the motor and of the sign shifting chains, particularly when a universal motor is used, the shaft 50 is provided with a centrifugal governor 56, which is connected by crank arms 57 and 58 on a rocker shaft 59, and by a link 60 with a vertically and longitudinally movable brake or drag bar 61, arranged to engage with the upward run of one of the chains 20 between the adjacent guide plate 13 and the front of the casing. The bar 61 is formed with inclines engaging corresponding inclines 63 on the adjacent end plate 1, as shown in Fig. 3. The lower reduced end of the bar 61 passes loosely through a lug 65 on a lever 66, which is fulcrumed at one end on the adjacent end plate of the casing and is formed at the other end with an incline engaging a longitudinal lever 67, which is fulcrumed as shown in Fig. 1, at the back of the casing. A spring 69, interposed between the lug 65 and an adjustable collar 70 on the brake bar 61, tends to shift the bar upwardly and thus reduce its pressure against the chain 20, with which it engages. At the end opposite that which engages with the lever 66, the lever 67 is bent outwardly, passing through a slot in the back of the casing, and is provided with a vertically elongated opening through which the pulley belt passes, as shown in Fig. 2. The outwardly bent end of the lever 67 is formed with a series of notches 81, which correspond in spacing with the steps of the cone pulley 49, and are adapted by engagement with the back of the casing at the upper end of the slot therein, to lock and hold said lever in adjusted position corresponding with the desired speed of the motor and of the shifting signs.

The glass plate or pane 11 through which the shifting signs are exposed to view, corresponds in thickness with the signs, and forms at its upper edge a ledge for supporting a stationary sign 83 in position for exposure to view through the upper sight opening, the back of the stationary sign being in the same plane with the inner face of the glass plate or pane 11, thus providing a continuous plane surface for guiding the shift-

ing signs and holding them in a vertical position as they are shifted upwardly from the sight opening.

The trunnions 18 are located above the longitudinal centers of the signs, so that the signs suspended thereby from the guideways, tend to maintain a vertical position during the passage of the trunnions therethrough.

10 The signs, which may be made of any suitable material, preferably consist as shown, of sheet metal holders folded around the edges to engage with and hold sheets 85, of cardboard or other material, on which the advertising or other matter to be displayed, is printed or otherwise shown. These sheets to which the matter to be displayed is applied, thus can be easily removed and replaced by sheets with other matter thereon. Spaces 20 are left between the adjacent ends of the brake shoes or bars 14 and 15, to permit the trunnions 18 to be lifted from the guideways, so that the signs can be readily removed and replaced for changing the matter 25 thereon or for any other purpose, the top section 5 of the casing being removable to afford access to the signs.

For illuminating both the shifting and stationary signs at night, or in dark places, 30 the machine is provided in the forward extension of the base with removable cages 87, having sockets and connections for electric lamps or bulbs 88. These cages, which also serve as reflectors, are open at the top and are supported in operative position by engagement with the front angle bar 4 and with downwardly projecting flanges 90, which may be integral with or attached to the top of the front section 7 of the casing. 35 The top wall of the base extension formed by the casing section 7, is provided with glazed openings 92, through which the light rays from the lamps 88 are projected and reflected upwardly against the movable sign 40 17 exposed to view through the lower sight opening and against the stationary sign 83, exposed to view through the upper sight opening of the casing.

The sheet metal casing section 7 is extended inwardly, and upwardly flanged as shown in Fig. 2, to support the lower edges of the glass or transparent panes or plates 10 and 11.

In the operation of the machine, the brake 55 shoes or bars 14 and 15 are adjusted to bear with sufficient pressure on the sign trunnions 18 during their passage rearwardly and downwardly through the guideways, to equalize the load on the motor, prevent the signs 60 from falling away from and out of engagement with the lugs 26 on the chains in their downward passage through the rear vertical stretches of the guideways, and obtain a steady uniform movement of the signs 65 throughout their upward, rearward and

downward passage through the guideways from the sight opening in the front of the casing to the rear ends of the lower transverse stretches of the guideways forming the magazine.

With each complete circuit of the chains 20, which are driven in unison by the sprocket wheels 22 on the shaft 28, the lugs 26 in their upward passage engaging the trunnions 18 of the front sign 17 in the 70 magazine, shift the sign upward from the lower sight opening in the casing, then backward and then downward, till the trunnions 75 engaging with the upwardly curved rear ends of the plates 16 are deflected into the lower transverse storage parts of the guideways, and the sign is pressed forward by the springs 41 against the rear sign of the series facing the sight opening. As the front sign is withdrawn upward from the series as 80

above stated, the signs behind it are moved forward by the springs 41, aided by the downward inclination of the lower parts of the guideways, and the next sign is brought into place opposite the sight opening. Any 85 fluctuation in the speed of the motor and hence in the movement of the signs, which may not be remedied by the brake shoes or bars 14 and 15 owing to lack of proper adjustment or otherwise, is taken care of by 90 the governor 56. In case of an increase above normal speed, the governor tends to shift the brake bar 61 downward, causing the incline 63 to increase its pressure against the adjoining chain 20, thereby checking the 100 speed of the motor by increasing the load thereon. On the other hand, in case of a decrease below normal speed, the balls of the governor are drawn toward each other by the spring connecting them, thus permitting the spring 69 to force the brake bar 105 61 slightly upward, and reducing its pressure against the adjoining chain, so that the motor and the chains will resume their normal speed.

As the chains 20 are carried by the sprocket wheels 22 a considerable distance below the guideways in which the signs are held and travel, the signs will be exposed to view one after another for intervals of time 115 corresponding with the time required for the lugs 26 to make a complete circuit, so that the length of exposure of the signs may be varied by varying the speed of the motor, and hence of the chains. This is accomplished by shifting the belt which connects the motor pulley 47 with the cone pulley 49. Shifting the belt from a larger to a smaller part of the cone pulley, increases the speed 120 of the chains, and the time of exposure of the signs is correspondingly shortened. To shift the belt from a larger to a smaller part of the pulley, the outwardly bent end of the lever 67 is first pressed down out of engagement with the back section 6 of the cas- 125 130

ing, and then pulled backward the required distance to carry the belt upon the desired step or part of the cone pulley, and is then released so that the proper notch 81 will engage with said back section and lock the lever in place. With a shifting of the belt to smaller parts of the pulley 49 to increase the speed of the motor as above explained, the opposite end of the lever 67 engaging the incline on the rear end of the lever 66, 10 slightly elevates the lug 65, thereby increasing the tension of the spring 69, which tends to thrust the drag bar 61 upward and reduce its pressure against the adjoining chain 20. 15 An increase in the speed of the motor and sign shifting chains is thus permitted.

In like manner, to reduce the speed of the motor and chains and thus increase the time of exposure of the signs, the notched end of the lever 67 is moved forward into the case, 20 carrying the belt with it, into engagement with a larger part of the cone pulley 49. With this movement of the lever 67, the lever 66 with the lug 65, is slightly lowered, reducing the tension on the spring 69 and its 25 resistance to the action of the governor, which operates to draw the brake bar 61 downward on the inclines 63 and increase its pressure against the adjoining chain 20, thereby increasing the load and causing the 30 motor to run at a slower speed. Without this provision for adjusting the tension of the spring 69 for different speeds, according to the position of the belt on the cone pulley 49, an increase in speed of the motor acting 35 through the governor would be counteracted by the action of the brake bar 61. Conversely, a decrease in the speed of the motor would be prevented by the compensating action 40 of said brake bar.

The stationary sign 83 may consist, as shown in Fig. 2, of a holder from which the trunnions are omitted, and in which sheets 85, of cardboard or other material bearing the advertising or other matter for display, are inserted, so that such matter can be easily changed from time to time as desired.

The electric light cages 87 are easily removed for renewing the lamps 88, by shifting the cages towards the ends of the casing 50 out of engagement with the flanges 90, then shifting them backward out of engagement with the front angle bar 4, when they can be withdrawn through the open bottom of the casing.

Various changes in the details of construction and arrangement of parts of the machine may be made without materially affecting its mode of operation and without departing from the principle and scope of the invention as defined in the following claims.

I claim:

1. In a shifting-sign machine, the combination of a casing having a sight opening in

one side and having its interior at its ends provided with aligned guides for determining closed paths of movement for sign guiding and supporting trunnions, disconnected signs provided at their ends with sign guiding and supporting trunnions, flexible means confined to travel only in part in correspondence with said closed paths of movement and adapted to engage said trunnions so as to positively move a sign through a predetermined part only of its entire predetermined closed path of movement, motor mechanism for actuating said flexible means, and means to tilt said signs to prevent interference of one sign with another sign. 70 75 80

2. In a shifting-sign machine the combination of a casing having a sight opening in the front side and provided at the ends with parallel guideways the lower parts of which are transverse to the ends of the casing adjacent the sight opening, signs provided at the ends with trunnions adapted to traverse the guideways, chains guided in the casing along and below the guideways and provided with lugs adapted to traverse the guideways and by engagement with the trunnions to shift the signs one at a time from the sight opening upward, backward and downward into engagement with the rear ends of said lower transverse parts of the guideways, a motor for actuating the chains, and a brake acting on the downwardly moving signs as they traverse the descending rear parts of the guideways to hold the signs against falling away from the lugs on the chains and to equalize the load on the motor. 85 90 95 100 105

3. In a shifting-sign machine the combination of a casing having a sight opening in front and provided at the ends with parallel guideways the lower parts of which are transverse to the ends of the casing adjacent the sight opening, signs provided at the ends with trunnions adapted to traverse the guideways, chains guided in the casing and provided with lugs arranged to traverse the guideways and by engagement with the trunnions to shift the signs one after another from the sight opening upward, backward and downward into engagement with the rear ends of said lower transverse parts of the guideways, a motor for actuating the chains in unison, and brakes acting on the sign trunnions as they traverse the rear descending parts of the guideways, to equalize the load on the motor and to prevent the trunnions in their descent from falling away from the lugs on the chains. 110 115 120 125

4. In a shifting-sign machine the combination of a casing having a front sight opening and provided at the ends with parallel guideways the upper and lower parts of which are transverse to the ends of the casing, signs provided at the ends with trunnions adapted to traverse the guide- 130

- ways, chains guided in the casing along and below the guideways and provided with lugs adapted to traverse the guideways and by engagement with the trunnions to shift the signs one after another from the sight opening upward, backward and downward into engagement with the rear ends of the lower transverse parts of the guideways, a motor for actuating the chains in unison, and brakes arranged to act on the sign trunnions as they traverse the upper transverse parts of the guideways in engagement with the lugs on the chains for equalizing the load on the motor.
15. 5. In a shifting-sign machine the combination of a casing having a sight opening and endless parallel guideways parts of which are adapted to support a number of signs assembled one behind another facing said opening, signs provided at the ends with trunnions adapted to traverse the guideways, chains guided in the casing along and below the guideways and provided with lugs adapted by engagement with the trunnions to shift the signs one after another from the sight opening upward, backward and downward to a position behind the assembled signs, a motor for actuating the chains, and brakes engaging the sign trunnions as they traverse the upper transverse and rear vertical parts of the guideways.
6. In a shifting-sign machine the combination of a casing having a sight opening and endless parallel guideways parts of which are adapted to support a number of signs assembled one behind another facing said opening, signs provided at the ends with trunnions adapted to traverse the guideways, chains guided in the casing along the front, upper and rear parts of the guideways and below the lower parts thereof and provided with lugs adapted by engagement with the trunnions to shift the signs one after another from the front to the rear ends of the parts of the guideways supporting the assembled signs, a motor for actuating the chains, and adjustable yielding brakes engaging the sign trunnions as they traverse the rear vertical parts of the guideways.
7. In a shifting-sign machine the combination of a casing having a sight opening and endless parallel guideways parts of which are adapted to support a number of signs assembled one behind another facing said opening, signs provided at the ends with trunnions adapted to traverse the guideways, chains guided in the casing and provided with lugs adapted by engagement with the trunnions to shift the signs one after another from the front to the rear of the assembled signs, a motor for actuating the chains in unison, an adjustable brake acting on one of the chains, and a centrifugal governor connected with the brake for regulating the speed of the motor and chains.
8. In a shifting-sign machine the combination of a casing having a sight opening and endless parallel guideways parts of which constitute a magazine adapted to support a number of signs assembled one behind another facing said opening, signs provided at the ends with trunnions adapted to traverse the guideways, chains provided with lugs adapted by engagement with the trunnions to shift the signs one after another at intervals from the front to the rear of the magazine, a motor for driving the chains in unison, an adjustable brake engaging one of the chains, a spring tending to release the brake, a centrifugal governor driven by the motor and connected with the brake, a change speed transmission between the motor and chains, and a connection between the change speed transmission and the spring adapted to increase the tension of the spring when the change speed transmission is adjusted to increase the speed of the chains.
9. In a shifting-sign machine the combination of a casing having a sight opening, parallel vertical flanges and endless parallel guideways at the ends of the opening, the lower parts of the guideways constituting a magazine adapted to support a number of signs assembled one behind another facing said opening and the inner vertical flanges forming parts of the front vertical runs of the guideways, signs provided at the ends with trunnions adapted to traverse the guideways, chains guided in the casing and provided with lugs adapted by engagement with the trunnions to shift the signs one after another from the front to the rear of the magazine, a motor for driving the chains in unison, a transparent plate held at the ends between said vertical flanges in the lower part of the sight opening opposite the front sign in the magazine, and a stationary sign held at the ends between said flanges in the upper part of the sight opening and resting on the upper edge of said transparent plate with which it forms a continuous guiding surface for the shifting signs in their upward movement from the magazine.
10. In a shifting-sign machine the combination of a casing having a sight opening and a forwardly extending base having an opening in the top below the sight opening, a number of movable signs, mechanism for shifting said signs at intervals one after another into and out of view through the sight opening, and a lamp in the base extension arranged to project light upwardly through said openings upon the sign exposed to view through the sight opening.
11. In a shifting-sign machine the com-

bination of a casing having a front sight opening and a forwardly extending base having an opening in the top below the sight opening, a number of movable signs, mechanism for shifting the signs at intervals one after another into and out of view through the sight opening, an open top lamp cage removably mounted in the base exten-

sion and provided with an electric lamp arranged to project light upwardly through said openings upon the sign exposed to view through the sight opening. 10

In witness whereof I hereto affix my signature.

ULRICH ANDERSON.
